UNITED STATES PATENT OFFICE.

ONESIME E. MICHAUD, OF ST. LOUIS, MISSOURI.

SHOTGUN.

No. 927,573.

Specification of Letters Patent.

Patented July 13, 1909.

Application filed March 15, 1909. Serial No. 483,487.

To all whom it may concern:

Be it known that I, ONESIME E. MICHAUD, a citizen of the United States, and a resident of the city of St. Louis and State of Missouri, have invented a new and useful Improvement in Shotguns, of which the following is a specification.

This invention relates to shotguns and more particularly to double-barreled guns.

10 It has for its principal objects to facilitate the attachment of a removable extension or choke muzzle section, to secure rigidity of attachment, and to prevent accidental displacement.

15 The invention consists in the parts and in the arrangements and combinations of parts hereinafter described and claimed.

20 In the accompanying drawing forming part of this specification and wherein like symbols refer to like parts wherever they occur, Figure 1 is a top plan of the forward end portion of a double-barreled shotgun with a removable muzzle section embodying my invention attached thereto, a portion of 25 said muzzle section being shown in section; Fig. 2 is an inverted bottom view of the same; Fig. 3 is a view partly in side elevation and partly in section on the line 3—3 of Fig. 1; and, Fig. 4 is an elevation of the 30 inner end of the removable muzzle section detached from the gun.

The gun is a double-barreled gun of ordinary type. Close to the muzzle, the top of the midrib 1 between the barrels 2 is provided with two oppositely disposed notches 3, thereby forming a T-shaped attaching portion 4. Any ordinary sight 5 may be secured at the usual place on the top of the midrib.

40 The removable muzzle section is a short member comprising a midrib 6 and two barrels 7. These sections may be made in interchangeable sets of various lengths or choke bored to suit all purposes. The rear end of 45 this muzzle member is finished to form a butt-joint with the end of the gun barrels, so that its bores are continuous with those of the gun barrels. A small flange 8 extends around the greater portion of the rear end 50 of the removable member, and said flange decreases gradually in depth toward the bottom portions of the barrels where it disappears altogether near each side of the midrib 6. At the top of the member on each 55 side of the midrib are two rearward extensions 9 having oppositely disposed inturned

end portions 10 which are made to fit the notches 3 in the midrib 1 of the gun proper, the rectangular space between said extensions being a counterpart of the T-shaped 60 attaching portion 4 at the forward end of said midrib 1.

An elongated locking member 11 having a vertical longitudinal slot therein is fitted over a lug 12 on the bottom of the midrib 6. The forward end portion of the longitudinal slot in said locking member 11 is reduced in width; and the sides and front end of said lug 12 are undercut or notched at the base thereof so as to receive said narrower slotted portion. To secure the locking member 11 in place the forward end portion thereof is perforated to receive a screw 13 which is fitted in a threaded hole in the midrib 6. This locking member is a 75 strong spring which lies normally in contact flatwise with the bottom of the midrib. It has a lug or stud 14 on its free end portion which is adapted to fit in a counterpart hole or depression in the bottom of the midrib 80 of the gun proper. The locking member is provided with two lugs 15 which constitute a support for a horizontal pintle 16; and on this pintle is pivoted a cam lever 17. Normally, this lever lies in the vertical, longitudinal slot in said spring locking member with the end of its short member 18 in an undercut or notch in the forward end of a lug 19 on the bottom of the midrib 6 at the rear end thereof. This lug 19 fits into the 90 rear end portion of the slot in said spring locking member. The short end portion of the lever 17 is of such length that, when the muzzle member is locked on the gun proper the turning of the lever perpendicularly to the midrib will lift the rear end of the locking member 11 with its stud or projection 14 clear of the midrib 1 of the gun. The long arm of the lever 17 is of such length that, when it is folded into the slot in the 95 member 11, it reaches nearly to the lug 12 on the bottom of the midrib 6. Pivotally mounted on the outer face of the lever 17 near its outer end is a latch member 20 which is adapted to engage with the lug 12 100 to hold the lever in closed position. Preferably, the long arm of the lever 17 is a very strong spring and its end portion may be tapered or bent slightly outward, or, the bottom of the midrib 6 may obviously be 105 grooved slightly to permit the end portion of the lever to be pressed inwardly to allow

the end of the latch member 20 to be moved under a projection or engaging portion 21 which may be formed by notching the rear end of the lug 12 as shown. To prevent the 5 latch member from being accidentally disengaged from the projection 21, the sides of said portion are preferably tapered or slightly pointed so as to fit in a depression or groove 22 in the outer face of the latch 10 member.

Obviously, instead of providing a lug or stud 14 on the spring locking member 11 which is adapted to fit in a counterpart hole in the bottom of the midrib 1, the arrangement 15 may be reversed; that is, the stud may be provided on the midrib and the hole in the locking member, or the slot in said locking member may be extended farther toward the rear so as to fit over the stud.

20 The operation of mounting the muzzle section is as follows: Assuming that the gun is in a horizontal position, the rear end of the muzzle section is inclined downwardly and its projections 9 are placed with their 25 inturned ends 10 in the notches 3 in the top of the midrib 1. The cam lever 17 is turned up perpendicular to the midrib 6 of the muzzle section to raise the free end of the spring locking member 11, and the muzzle 30 section is tilted down until it fits squarely against the end of the gun; the gradual reduction in the depth of the circular flanged portions 8 permitting of this fitting movement. Then the cam lever 17 is depressed so that the spring locking member 35 11 lies flush against the bottom surfaces of the midribs of the gun proper and the muzzle section with its stud 14 in the hole provided therefor in the bottom of the midrib 40 1. In the closed position of the lever, its short arm and portion of the long arm adjacent to the pivot also rest flush against the bottom of the midrib of the muzzle section; and the end of the short arm fits tightly in 45 the notch or undercut in the lug 19. When the parts are in proper position the end portion of the lever 17 is depressed so that the pivoted latch member 20 may be moved under the projection 21. When the lever is 50 relieved of the pressure thereon, the resiliency of the lever holds the latch member 20 with its notched portion 22 in engagement with said projection 21. In order to detach the muzzle section, it is merely necessary to raise the cam lever, thereby disengaging the spring locking member, and then tilt or swing the muzzle section upwardly to disengage the upper portion 55 thereof.

60 It is noted that while the flanged or bell portion 8 is gradually diminished toward the bottom to facilitate the attachment of the muzzle section to the gun, there is a sufficient overlapping portion to give stability to the attachment. It is also noted 65

that the appearance of the gun is not marred by the use of my attachment; that the attachment does not interfere with the use of the ordinary sight on the gun; and that owing to the absence of movable projecting 70 portions there is little liability of accidentally opening the locking device.

Obviously, my device admits of considerable modification without departing from my invention, and, therefore, I do not wish 75 to be limited to the specific construction shown and described.

What I claim is:

1. A double-barreled shotgun having attaching portions at the forward end of its 80 midrib on the top and bottom thereof, a removable muzzle section having bores arranged to constitute a continuation of the bores of the gun proper, said removable muzzle section also comprising a midrib, a 85 counterpart attaching portion on said muzzle section adapted to interlock with the attaching portion on the top of the midrib of the gun proper, and a locking device on the bottom of the midrib of the removable 90 muzzle section comprising two lugs on said midrib, a slotted locking member secured at its end to the forward portion of said midrib and adapted to lie flatwise against said midrib, a counterpart attaching portion on 95 said slotted locking member adapted to interlock with the attaching portion on the bottom of the midrib of the gun proper, a cam lever mounted on said slotted locking member and arranged to bear against the 100 midrib of the removable muzzle section and adapted to move the rear end of said locking member transversely, the short arm of said lever being arranged to engage one of the lugs on the bottom of the midrib of the removable muzzle section when said lever is lowered, and a latch member on the end of the long arm of said lever arranged to engage the opposite lug on the bottom of said last mentioned midrib.

2. A double-barreled shotgun having attaching portions at the forward end of its midrib on the top and bottom thereof, a removable muzzle section having bores arranged to constitute a continuation of the 115 bores of the gun proper, said removable muzzle section also comprising a midrib, counterpart flanged portions arranged to overlap the end portion of the gun proper, said flange diminishing toward the bottom of said muzzle section, a counterpart attaching portion on said muzzle section adapted to interlock with the attaching portion on the top of the midrib of the gun proper, and a locking device on the bottom of the midrib of the removable muzzle section comprising two lugs on said midrib, a slotted locking member secured at its end to the forward portion of said midrib and adapted to lie flatwise against said midrib, a counterpart attaching portion 120

110

115

120

130

portion on said slotted locking member adapted to interlock with the attaching portion on the bottom of the midrib of the gun proper, a cam lever mounted on said slotted locking member and arranged to bear against the midrib of the removable muzzle section and adapted to move the rear end of said locking member transversely, the short arm of said lever being arranged to engage one of the lugs on the bottom of the midrib of the removable muzzle section when said lever is lowered, and a latch member on the end of the long arm of said lever arranged to engage the opposite lug on the bottom of said last mentioned midrib.

3. A double-barreled shotgun having attaching portions at the forward end of its midrib on the top and bottom thereof, a removable muzzle section having bores arranged to constitute a continuation of the bores of the gun proper, said removable muzzle section also comprising a midrib, a counterpart attaching portion on said muzzle section adapted to interlock with the attaching portion on the top of the midrib of the gun proper, and a locking device on the bottom of the midrib of the removable muzzle section, comprising a lug on the bottom of said midrib near the forward end thereof, the sides and front end of said lug being undercut at the base thereof, a lug on the bottom of said midrib at the rear end thereof, said last-mentioned lug being undercut on its front end, a longitudinally

slotted spring locking member secured at its 35 end to the forward portion of said midrib, the forward end portion of said longitudinal slot being reduced in width and adapted to fit the undercut portions of said first mentioned lug on said midrib, said spring locking member being adapted to lie normally flatwise against the bottom of said midrib, a counterpart attaching portion on the free end of said spring locking member adapted to interlock with the attaching portion on 40 the bottom of the midrib of the gun proper, a cam lever mounted on said spring locking member and arranged to bear against the midrib of the removable muzzle section and adapted to move the rear end of said spring 45 locking member transversely, the short arm of said lever being arranged to engage the undercut portion of the lug on the rear end portion of the midrib of said removable muzzle section when said lever is lowered, 50 and a latch member pivoted on the end portion of the long arm of said lever and arranged to engage under a projection on the lug on the forward end portion of the midrib on said removable muzzle section. 55

In witness whereof I have signed my name to this specification in the presence of two subscribing witnesses this 13th day of March, 1909, at St. Louis, Missouri.

ONESIME E. MICHARD.
